UNITED STATES PATENT OFFICE.

JAMES M. HOOD, OF RANGER, TEXAS.

SAND-TRAP.

1,388,040.

Specification of Letters Patent. Patented Aug. 16, 1921.

Application filed November 29, 1919. Serial No. 341,346.

To all whom it may concern:

Be it known that I, JAMES M. Hood, a citizen of the United States, residing at Ranger, in the county of Eastland and State of Texas, have invented certain new and useful Improvements in Sand-Traps, of which the following is a specification.

This invention relates generally to sand traps, and more particularly to devices for preventing accumulation of sand in irrigation canals and ditches.

The principal object of the invention is to provide means whereby sand is removed automatically from irrigation canals and ditches through the medium of water flow and pressure.

Another object of the invention is to provide a suitable conduit whereby sand may be removed from an irrigation canal and ditch and carried to some point at a distance therefrom.

A still further object of the invention is to construct in conjunction with the improved sand hoppers an auxiliary water pipe contained therein and adapted for clearing the conduit of any sand which might settle in it.

Other improvements and novel details in the construction and arrangement of the various parts of the sand trap will be brought out more in detail in the description to follow, which, for clear understanding of the invention should be considered in connection with the accompanying drawings forming a part of the specification, and wherein is disclosed for the purpose of illustration a convenient and satisfactory embodiment of the invention.

In the drawings:

Figure 1 is a cross sectional elevation of an irrigation canal or ditch having my invention installed therein.

Fig. 2 is a detail cross sectional view of my invention *per se*.

Fig. 3 is a detailed view of a section of the sand hopper and water supply pipe.

Fig. 4 is a detail view of the valve operating mechanism.

Like characters of reference designate like or similar parts throughout the several views.

As illustrated in Fig. 1 of the drawing the letter A designates a canal or irrigation ditch, the bottom of which is excavated to receive my invention which is designed to lie flush therewith in order that sand moved

along the bottom by the flow of water will be intercepted and disposed of.

Referring particularly to Fig. 2 the casing 1, which is preferably rectangular in configuration and of a size depending upon the breadth of the canal or ditch, is provided with a series of compartments or chambers generally designated by 2 and separated by a plurality of transverse partitions, one of which is shown and designated by the numeral 3. In order to prevent the ingress of large objects such as stones to the casing a wire netting or screen 4 is mounted to cover the whole open portion thereof.

Mounted in each of the chambers 2 is a substantially V shaped trough having sides 5 and a bottom 5', the sides 5 having formed on their upper edges flanges 6 provided with openings 7 through which suitable securing means, such as screws or nails, may be passed to attach the trough to the edges of the casing and partitions. Attention is invited to the fact that the same means for securing the netting may be utilized for securing the flanges to the casing and partitions.

Mounted on the alternate side of each of the troughs and extending from the upper edge to a point slightly spaced from the bottom thereof are supplemental water conduits 8 generally designated by 8 each having a somewhat cylindrical depressed central portion 9 provided with flanges 10 for securing to the sides 5.

A drain pipe 11 is provided with service connections 12 extending through openings in the bottom of the casing communicating with each of the compartments. The said connections 12 are slightly spaced from the bottom of the trough and are adapted to register with openings 13 formed therein. The upper termination of each service connection is provided with an annular flange 14 the purpose of which will hereinafter appear.

As means for closing communication between the trough 2 and the drain pipe 11 a slide valve 15 movable between the upper termination of the service connections and the bottom of the trough and having openings adapted to periodically register with the openings in the trough and the service connections is mounted to extend to any member in the series of compartments and has a reduced portion 16 formed on one end

110

and provided with openings for receiving chains 17 carried by the valve lever 18 which extends upward above the surface of the canal or ditch.

5 In operation the sand carried down by the flow of water in the canal or ditch passes over the sand trap and upon settling is carried into the troughs 2. A continual flow of water through the troughs 2, service connections 12, the drain pipe 11 causes the sand to pass down to the drain pipe 11 and off to some point at a distance from the canal where it is deposited. Sand, which accumulates in the troughs during periods when the 15 slide valve 15 is maintained in closed position, settles into a compact mass which frequently does not readily flow through the ports 13 when the valve is opened. For this reason the supplemental conduits 8 are provided which take water from the ditch at a point above the level of the sand in the trap and discharge it at a point in close proximity to the ports 13. The relatively small quantity of sand lying intermediate the 20 lower terminal of each supplemental water conduit 8 and the ports 13 is quickly cut by the current of water passing through said conduit and is carried into the drain pipe 11. The body of sand gradually settles in 25 the trap and, mixing with the water supplied by the supplemental water conduit is entirely carried off by the drain pipe. It is to be noted further of the arrangement of the conduits 8 that the upper ends of the 30 same are always open to the inflow thereto of the water in the ditch, and that the lower end of the same is disposed immediately adjacent the outlet from the trough, so that the weight of the water above the trough 35 naturally tends to accelerate the flow downward thereof. Furthermore, when the valves 15 are open and sand and water is flowing through the pipe line 11, a suction is created at the lower end of the conduits 8 which additionally accelerates such down- 40 flow through the latter.

As drainage canals or ditches are generally arranged in series the water from one ditch or canal may be carried by the drain pipe 50 11 to another canal on a lower level and intermediate the two canals a point of deposit may be disposed so that none of the water may be lost while the sand and silt may be effectually separated therefrom.

55 When it is desired to place the device out of operation the valve lever 18 is turned consequently moving the valve 11 to close the opening 13 and severing communication between the trough and the drain pipe 11.

From the foregoing description taken in 60 connection with the accompanying drawings, it is thought that a clear and comprehensive understanding of the construction, operation and advantages of my invention may be had, and while I have shown and described the 65 device as embodying a specific structure, I desire that it be understood that such changes may be made in said structure as do not depart from the spirit and scope of the invention as claimed. 70

What I claim is:

1. A sand trap comprising a casing disposed in the bottom of a ditch, partitions in the casing forming compartments, means in the compartments for trapping sand and silt, and means communicating with said first named means for carrying off the sand and silt so trapped. 75

2. A sand trap comprising a casing disposed in the bottom of a ditch, partitions in the casing forming compartments, V shaped troughs in the compartments for trapping sand and silt, means communicating with said troughs for carrying off sand and silt so trapped, and means for preventing clogging of said first named means. 80

3. A sand trap comprising a casing disposed in the bottom of a ditch, partitions in the casing forming compartments, V shaped troughs in the compartments for trapping sand and silt, means communicating with said troughs for carrying off sand and silt therefrom by water flow and pressure, and a water conduit in the trough for preventing clogging of the said means for carrying 90 off sand and silt. 95

4. A sand trap comprising a casing disposed in the bottom of a ditch, a screen for the casing, partitions in the casing forming compartments, V shaped troughs in the compartments for trapping sand and silt, a drain pipe communicating with said troughs for carrying off sand and silt through water flow and pressure, means for severing communication between the drain pipe and 100 troughs, and auxiliary water conduits in the troughs for preventing clogging of the drain pipe. 105

5. A sand trap comprising a trough disposed on the bed of a body of water, means 110 for conveying the trapped sand and silt from said trough, and means disposed in said trough to prevent clogging of said means.

In testimony whereof, I affix my signature hereto. 115

JAMES M. HOOD.
